(**) Term: **14 Years**

CLAIM

(21) Appl. No.: **29/125,846**

The ornamental design for a crawl space door and frame
with interior and exterior flange, as shown and described.

(22) Filed: **Jun. 30, 2000**

DESCRIPTION

(51) LOC (7) Cl. **25-02**
(52) U.S. Cl. **D25/48**
(58) Field of Search D25/47-49, 52,
D25/60-61, 199; 52/169.1, 169.6, 169.12,
302.1, 303.3, 302.7, 202, 211; 454/195;
49/504; 269/905

(56) **References Cited**

FIG. 1 is a top plan view of a crawl space door and frame
with interior and exterior flange showing our new design;
FIG. 2 is a top plan view of a crawl space frame with interior
and exterior flange shown separately for clarity of illustration;

FIG. 3 is a top and side perspective view of the door and
frame as shown in FIG. 1;

FIG. 4 is a top and side perspective view of the frame as
shown in FIG. 2;

FIG. 5 is an enlarged top plan detail view of the frame shown
in FIG. 2; and,

FIG. 6 is an enlarged top perspective detail view of the door
shown in FIG. 1 shown separately for clarity of illustration.
